UNITED STATES PATENT OFFICE.

JOHN F. O'CONNOR, OF CHICAGO, ILLINOIS, ASSIGNOR, BY MESNE ASSIGNMENTS, TO
W. H. MINEE, INC., A CORPORATION OF DELAWARE.

LOCOMOTIVE DRIVING BOX.

Application filed August 29, 1924. Serial No. 734,833.

This invention relates to locomotive driving boxes.

An object of the invention is to provide a simple and efficient wear compensating device for use in connection with the brasses or liners provided in locomotive driving boxes, such device being arranged to compensate for wear in such a manner as to avoid or minimize lateral movement or play of the axles longitudinally of the locomotive.

A more specific object of the invention contemplates the use of a liner made up in sections, and the provision of eccentric arched seats to accommodate the sections of the liner, together with wedge means for effecting adjustment of said sections, to compensate for wear caused by the lateral movement of the axle longitudinally of the locomotive, such sections engaging the periphery of the axle from the top down to points horizontally disposed below the axial center thereof, vertical wear on the liner sections, which is greatest in extent, being automatically taken up by the action of gravity.

Other and further objects of the invention will more clearly and fully appear from the description and drawings hereinafter following.

In the drawings, Fig. 1 is a front elevation, al view, partly in section, of a fragment of the underframe of a locomotive, containing a driving box, showing the application of the invention thereto. And Fig. 2 is a view, partly in section, on the line 2-2 of Fig. 1.

Referring more particularly to the drawings, A represents the body portion of a locomotive side frame, including the usual pedestals B, and pedestal brace C. The driving box may be of any desired construction, provided with the customary shoe D and wedge E, a driving axle of the locomotive being indicated at F.

As contemplated by my invention, the driving box is provided with oppositely disposed merged arcuate seats indicated by the numerals 3 and 4. The curve of each of the seats 3 and 4 preferably has a radius about equal to that of the axle, and each seat is of such form that a continuation of one portion of the curve thereof will intersect the periphery of the axle, preferably at a point below the axis thereof, while the outer portions of said curved seats are spaced from the periphery of said axle. In other words, the center of

with reference to the axial center of the axle. The lower extremities 5 of both seats 3 and 4 are preferably disposed a short distance from the periphery of the axle, so as to permit the use of a liner having a substantial thickness at 60 these points.

The driving box liner usually heretofore employed is cast in one piece, and is forced into its seat in the driving box under pressure. The liner embodying the present invention however, is formed in two sections, indicated by the numerals 6 and 7 respectively, which snugly fit between the axle F and seats 3 and 4. When the sections 6 and 7 are assembled, the resulting bearing is substantially continuous at the center as indicated at 8.

The section 6 of the liner has formed in its outer peripheral surfaces, adjacent the meeting edges of the liner sections, a plurality 75 of transversely disposed, spaced, wedge cavities 9, the wedge surfaces 10 of which are inclined toward the outer edge of the liner section, and inwardly toward the liner section 7, as shown in the drawings. The liner section 7 is provided with a plurality of wedge cavities 11, similar in all respects to the cavities 10, except that the wedging surfaces 12 of the cavities 11, are oppositely disposed with respect to the surfaces 10, and the surfaces 12 of the wedge cavities 11 are spaced 85 a suitable distance from the surfaces 10.

Disposed in the cavities 9 and 11 is a plurality of wedges 13, there preferably being one wedge for each cavity, and such wedges 90 are connected together, preferably by webs 14, the outer of the wedge portions 13 having connected therewith the end of an adjusting screw 15. The adjusting screw 15 extends through a plate 16, which may be fastened 95 to the structure of the driving box by means of screw bolts 17 as shown, and on the outer end of the screw 15 is threaded a nut 18, adapted to bear against the plate 16, to adjustably pull the wedges 13, so as to spread 100 the liner sections 6 and 7.

When worn, the liner sections 6 and 7 are spread apart and fed outwardly relatively to the seat, and circumferentially relatively to said axle, by means of the wedges 13, which 105 receive longitudinal movement through the medium of the adjusting screw 15. This effects adjustment of the liner portions 6 and 7, so that they are forced downwardly and inwardly toward points 5-5, such adjustment 110

compensating for the wear on the liners caused by the lateral movement of the axle horizontally relative to the driving box.

While I have herein shown and described what I now consider the preferred manner of carrying out the invention, the same is merely illustrative, and I contemplate all changes and modifications that come within the scope of the claims appended hereto.

I claim:

1. In a driving box for locomotives, the combination with a box member proper having an opening adapted to receive an axle, said opening having spaced side walls which are spaced from the axle, said box member proper being provided with a seat at the upper end thereof, said seat having curved unobstructed, continuous guide surfaces converging downwardly and inwardly toward the axle and merging with the side walls of the journal box opening; of a sectional liner mounted in said seat, said liner being arranged to bear directly on the axle, and the sections of the liner co-operating respectively with the curved guide surfaces of the seat; and means for adjusting the liner sections along said curved surfaces toward the axle, the adjusting movement of said liner sections being limited only by engagement with the axle.

2. In a device of the character described, the combination with a box provided with a walled opening adapted to receive an axle, said box having a seat presenting two separate curved bearing surfaces converging downwardly and inwardly toward the axle, said curved surfaces being continuous and merging with the side walls of the journal box opening, the bottom ends of said surfaces being unobstructed; of a sectional brass in said seat, the sections of said brass being adjustable along said bearing surfaces circumferentially of the axle and inwardly toward

the same; and means for wedging said sections apart circumferentially of the axle to force the bearing surfaces thereof toward said axle.

3. In a driving box for an axle, the combination with a box member proper having a walled opening adapted to receive the axle; of a sectional bearing liner for said box; seats on opposite sides of said box each having a continuous curved guide surface on which the sections of said liners bear respectively, the lower end portions of said continuous curved surfaces merging with the adjacent walls of the journal box opening, said curved surfaces of said seat members being eccentric with respect to each other, and the curved surfaces of both of said members being eccentric to the axial center of the axle; and means for spreading the sections of said liner apart to adjust the same on said curved surfaces of the seats circumferentially of the axle and laterally inwardly toward the same to compensate for wear caused by lateral movement of the axle with respect to the box.

4. In a driving box for locomotives, the combination with a driving box proper, having an opening adapted to receive an axle and provided above said opening with offset, arcuate seats, the lower edges of which merge with the surfaces defining said opening, whereby shoulders are eliminated; of a pair of approximately semi-crescent-shaped liners, each fitting one of said seats on its outer side and the axle on its inner curved side; and means for shifting said liners circumferentially on said seats and thereby projecting the lower edges of the liners into said opening.

In witness that I claim the foregoing I have hereunto subscribed my name this 19th day of August, 1924.

JOHN F. O'CONNOR.
